(57) CLAIM

The ornamental design for an inflatable couch float, as shown and described.

DESCRIPTION

FIG. 1 is a perspective view of an inflatable couch float, showing my design;

FIG. 2 is a front elevation view thereof;

FIG. 3 is a rear elevation view thereof

FIG. 4 is a right side view thereof;

FIG. 5 is a left side view thereof;

FIG. 6 is a top plan view thereof; and,

FIG. 7 is a bottom plan view thereof.

The broken lines illustrate portions of the inflatable couch float that form no part of the claimed design.
